CLAIM

The ornamental design for a combined drain oil collection and storage container, as shown and described.

DESCRIPTION

FIG. 1 is a perspective view of a combined drain oil collection and storage container showing my new design;

FIG. 2 is a front elevational view thereof;

FIG. 3 is a side elevational view of the right side thereof;

FIG. 4 is a rear elevational view thereof;

FIG. 5 is a side elevational view of the left side thereof;

FIG. 6 is a top view thereof; and

FIG. 7 is a bottom view thereof.
